UNITED STATES PATENT OFFICE.

GEORGE ENGELHART AND CHARLES WEIDNER, OF ATTICA, OHIO.

SHIFTING BUGGY-TOP.

SPECIFICATION forming part of Letters Patent No. 297,771, dated April 29, 1884.

Application filed December 13, 1883. (No model.)

To all whom it may concern:

Be it known that we, GEORGE ENGELHART and CHARLES WEIDNER, of Attica, in the county of Seneca and State of Ohio, have invented certain new and useful Improvements in Top-Buggies, of which the following is a full, clear, and exact description.

Our invention consists of a contrivance of the buggy-top supporting rail and the "lazy-back" supports, whereby the rail may be readily taken off without taking off the lazy-back when it is desired to remove the top and use the vehicle as an open buggy, all as hereinafter fully described.

Reference is to be had to the accompanying drawings, forming a part of this specification, in which similar letters of reference indicate corresponding parts in all the figures.

Figure 1 is a perspective view of a buggy-seat with the top-supporting rail and the lazy-back to the seat attached according to our invention. Fig. 2 is a detail of connecting devices and part of the top rail in perspective view and on an enlarged scale. Fig. 3 is a perspective view of one of the top-bar clips and seat-back supports. Fig. 4 is a perspective view of a section of the top-supporting rail, and Fig. 5 is a side elevation of the connecting devices and section of the top rail represented in Fig. 2.

We make the lazy-back supports *a* and the connecting devices for the arms *b* to consist of hook-clips *c*, having a screw-shank, *d*, to clip the top-supporting rail *e*, down on the seat-irons *f* by inserting the screws *d* through holes of seat-irons and securing them with nuts *g*, so that said top rail may be readily taken off by unscrewing the nuts, lifting up the clips, and removing the top-rail, and that said back-supports and arm-connections may be replaced and screwed up, as before, to retain the seat-back *h* in place, thus enabling the seat-back to be used when the top is removed.

To seat the top-rail *e* substantially on the seat-irons *f*, we construct it with flat-bottomed sections *h*, where it rests on the seat-irons, by which it has sufficiently wide bearings to be

firmly held when clipped thereon. We also make these bearing-sections *h* with an extension, *i*, reaching to the outer surface of the hook end of the clip, which is suitably notched at *j* to receive them, so that the clips will draw down on said extensions *i* for more substantially securing the rail both against any tendency of the rail to roll on the seat-irons and also against any lengthwise movements. The hook ends of the clips also bear firmly on the seat-irons at the side of these extensions when screwed down. The top-supporting rail *e* may also have stud-bolts *k*, when required, for connecting with seat-irons *f* intermediately to the places where the back-supports and arms are connected.

The advantage of the extensions *i* will more fully appear when the bolts at *k* are dispensed with, or rather when not used, and simply rests are used thereat, as is most frequently desirable, (although by the use of the extensions *i*, together with said bolts, the latter are prevented from being strained,) since, when the top-rail becomes worn and would be liable to shift or slide more or less in the clips, the extensions, disposed to fit into opposite notches of the clips, will prevent such movement.

Having thus fully described our invention, we claim as new and desire to secure by Letters Patent—

1. The top-supporting rail having the extensions, in combination with the notched hook-clips of the seat-back supports, said extensions fitting into opposite notches of said clips, substantially as and for the purpose set forth.

2. The top-supporting rail *e*, having flat-bottomed bearing-sections *h*, with extensions *i*, in combination with the notched hook-clips *c* of the seat-back supports *a* and arm *b*, and with the seat-irons *f*, substantially as described.

GEORGE ENGELHART.
CHARLES WEIDNER.
